UNITED STATES PATENT OFFICE.

GEORGE BLOHM, OF EL CENTRO, CALIFORNIA.

COTTON-HARVESTER.

1,242,761.

Specification of Letters Patent.

Patented Oct. 9, 1917.

Application filed April 20, 1917. Serial No. 163,492.

To all whom it may concern:

Be it known that I, GEORGE BLOHM, a citizen of the United States, residing at El Centro, in the county of Imperial and State 5 of California, have invented new and useful Improvements in Cotton-Harvesters, of which the following is a specification.

This invention relates to cotton harvesters and it has for its object to produce an organized machine of simple and improved construction whereby the cotton bolls may be stripped from the stalks, separated from a large proportion of impurities, and conveyed to a receptacle carried by the machine.

15 A further object of the invention is to produce a simple and improved machine of the class described in which the working parts will be mounted on a wheel supported platform, the vehicle as well as the moving 20 parts of the machine being driven by a motor installed on the platform.

25 A further object of the invention is to produce simple and improved mechanism for stripping or detaching the cotton bolls from the stalks, the said mechanism consisting of coacting rollers driven at uneven speed.

30 Further objects of the invention are to simplify and improve the construction, arrangement and operation of the detailed parts of the machine.

35 With these and other ends in view which will readily appear as the nature of the invention is better understood, the same consists in the improved construction and novel arrangement and combination of parts which will be hereinafter fully described and particularly pointed out in the claims.

40 In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings:

45 Figure 1 is a side elevation of a machine constructed in accordance with the invention.

Fig. 2 is a top plan view of the same.

50 Fig. 3 is a longitudinal sectional view taken on the line 3-3 in Fig. 2.

Fig. 4 is a front elevation.

Fig. 5 is a transverse sectional view taken 55 on the line 5-5 in Fig. 3.

Fig. 6 is a horizontal sectional detail view showing the brackets 27 and related parts.

Corresponding parts in the several figures of the drawings are denoted by like characters of reference.

The main frame of the improved machine includes sills or side members 15, the same being spaced apart and connected together by a platform 16, the frame structure being 65 supported on front and rear axles 17, 18 having wheels 19, 20, the rear wheels serving as traction wheels and the rear axle being driven by power derived from a motor A supported on the platform. The front 70 axle is connected with a steering gear generally designated by B and including a steering wheel 21 which is mounted in convenient proximity to the operator's seat 22.

The machine shown in the accompanying 75 drawings is adapted to operate simultaneously on two rows of plants and accordingly two sets of stripping apparatus are provided, one at each side of the forward end of the frame structure. Each set of stripping 80 apparatus has been shown as comprising two side bars namely an inner side bar 23 and an outer side bar 24, said side bars preferably consisting of angle bars having rearwardly extending arms 25 that are pivoted 85 on a shaft 26, said shaft being supported at its inner and outer ends in brackets 27, 28 projecting at the front end of the frame structure, said outer bracket having a slot 29 to permit the shaft and related 90 parts to swing to a limited extent in an approximately horizontal plane. The bars 23 and 24 are provided at their forward ends with divergent gathering arms 30 and 31, said gathering arms being relatively depressed 95 at their front ends so that when the parts are in position for operation, the said inner gathering arms will engage the ground at their forward ends while the outer arms 31 will be slightly elevated above 100 the ground. The said inner gathering arms may be provided with ground engaging rollers as indicated at 32 to prevent them from digging into the ground. The arms 30 and 31 will operate to gather the cotton 105 stalks between them in a manner and for a

purpose which will be presently hereinafter described.

The rearwardly extending arms of the inner and outer side bars 23 and 24 are pivoted 5 on the shaft 26 in such a manner as to permit a slight rocking movement of said arms in an approximately horizontal plane. Secured to the inner side bar 23 is one end of a cross bar 33 which extends beneath the outer side bar 10 24 and has an upturned end 34 which is connected with the vertical flange portion of the bar 24 by a bolt 35 having a nut 36, said bolt having a spring 37 coiled thereon, and said spring being interposed between the upturned portion 34 of the cross bar 33 and the vertical flange portion of the bar 24, pressing the latter resiliently in the direction of its mate 23. A brace bar 38 is connected at 15 its forward end with the bolt 35, the rearward end of said brace bar being adjustably connected by a bolt 39 with the forward end of the frame structure; the brace bar 38 being provided with a slot or with a plurality of apertures 40 for the passage of the bolt 39. It will be seen that by proper adjustment of the brace bar the side bars of the stripping device together with the shaft 26 on which they are mounted may be rocked in an approximately horizontal plane, owing 20 to the presence of the slots 29 in which the outer ends of the shafts 26 at the two sides of the machine are accommodated. By this simple adjustment it will be seen that the two sets of stripping apparatus may be 25 adjusted or rocked so as to be variously spaced apart at their forward ends, this provision being made to enable the machine to operate successfully on rows of plants that are variously spaced apart. It will also be 30 seen that the outer side bar 24 of each stripping apparatus is resiliently forced in the direction of the inner side bar, permitting the said outer side bar to rock against the tension of the spring 37 for the purpose of 35 varying the distance between the outer ends of the two side bars.

The side bars 23 and 24 of each stripping apparatus are provided at their forward ends with uprights 41 connected together by 40 a cap piece 42. The side bars 23 and 24 are also provided at their rearward ends with uprights 43 which are connected with the front uprights by suitable brace members 44. The front uprights 41 have brackets 45 supporting the upper ends of rotary shafts 46 the lower ends of which are stepped in the forward ends of the side bars 23 and 24. The shafts 46 carry coacting cylindrical rolls 47 which are preferably tapered at their lower ends as shown at 48, each of said rolls being provided with a spirally disposed rib 49. The shafts 46 carrying the coacting rolls are provided at their upper ends with pulleys 50 and 51, said pulleys being con-

nected by transmission bands 52 with driven 6 pulleys 53, 58 which are of unequal diameter and whereby the shafts carrying the coacting rolls will be driven at unequal speed. It is immaterial which of the two rolls is driven at relatively high speed but the rolls 7 must obviously be driven with their front portions moving each toward its mate so that plants engaged by the rolls will be forced to pass therebetween and at the same time be subjected to a rubbing or stripping 7 action due to the fact that the rolls are driven at unequal speed. The driven pulley 53 of each stripping device may receive motion from a countershaft 54 through the medium of intermeshing bevel gears 55, said countershaft being driven by a suitable transmission from the motor A. It may be appropriate at this time to state that the parts of the mechanism of the improved machine which are driven by the motor A 8 may be connected with the source of power by transmission means of any desired and well known character by including gear wheels, sprocket wheels, chains, pulleys, bands, and the like and that clutches or other 9 well known means for interrupting motion may be used wherever desired, together with levers and other like well known means for controlling such clutches and the like, but inasmuch as such transmission means are 9 well known and in general use, it is not deemed necessary to herein particularly describe or illustrate the same.

Supported on the frame structure to the rearward of each stripping device is a casting 56 containing a motor driven fan 57. Each fan case has an air inlet 58 and an air outlet 59, the latter communicating with a duct or wind trunk into which air will be forcibly discharged in a rearward direction. 1 The wind trunk 60 communicates at its forward end with a duct 61 supported on the side bars of the stripping apparatus and extending almost to the forward ends of said side bars where it terminates a short distance to the rearward of the stripping rolls 47. Connected with the forward end of each duct 61 is a shield 62 which extends upwardly and laterally and which serves to intersect, to spread and to flatten the cotton 1 stalks that pass between the stripping rolls. It will be evident that by the forcible discharge of air in a rearward direction in the wind trunk 60, suction will be set up in the duct 61 whereby the cotton bolls which are 1 detached from the stalks by the rubbing action of the coacting rolls 47, will be carried rearwardly through the duct and the wind trunk and discharged into a receptacle or cleaner case 63 with which the rearward end 1 of the wind trunk 60 is connected.

Arranged within the cleaner case 63 is a riddle C composed of a plurality of longi-

tudinal strips or bars 64 pivoted at their forward ends on a transverse rod or shaft 65 and serially connected at their rearward ends by a transverse rod 66, said rod 66 extending through slots 67 in the side walls 5 of the cleaner case. The strips or bars 64 are to be suitably spaced apart. The rod 66 is connected by means of links or pitmen 68 with wrist pins 69 on disks 70 mounted on 10 a driven shaft 71 whereby a vibratory motion will be imparted to the riddle. The cleaner casing also contains a driven cylinder 72 arranged to coöperate with the forward part of the riddle to engage the material passing into the cleaner casing through the wind trunk 60, rubbing the said material and separating the dust and the burs or squares from the cotton, permitting the heavy material to pass between the bars 15 of the riddle, while the light dust will be blown through an adjustable door or valve 73 in the top of the cleaner casing. The material passing between the bars of the riddle will fall on an inclined bottom plate 20 74 and will be thereby conveyed to the ground at a point near the rearward end of the cleaner casing.

Mounted on the supporting frame to the rearward of the cleaner case is a receptacle 30 75, said receptacle having been shown as a box of rectangular shape adapted to receive material discharged over the riddle C. Instead of discharging the cotton directly into the receptacle 75 I prefer to place in the latter a bag 76 of textile material, such as heavy ducking, the same being reinforced at its top edge by a bead 77 which may be constructed of a cord inclosed in a suitable hem and with which rings 78 are connected 35 to receive a draw string or rope 79 whereby the mouth of the bag may be closed. Mounted on a shelf 80 at one side of the receptacle 75 is a derrick 81 which may be utilized for hoisting the filled bag from the receptacle 40 75. The contents of the bag may be emptied 45 on the ground for subsequent gathering, or the bag may be replaced by an empty one provided that a sufficient number of bags are kept on hand to permit this procedure. 50 In such event a plurality of filled bags may be loaded on a truck or wagon and carried to the gin house.

It has been stated that when the machine is arranged for gathering cotton, the forward ends of the stripping devices will be supported by the ground engaging gathering arms 30. When the machine is to be transported from place to place it is necessary that the front ends of the stripping devices should be supported in raised position 55 with respect to the ground and to this end pivot arms 82 are provided, each of said arms having a notch 83 adapted to engage one of the countershafts 54, thereby sustain-

ing the stripping apparatus in a sufficiently 65 raised position to enable the machine to travel over the roads.

From the foregoing description, taken in connection with the drawings hereto annexed, the operation and advantages of this invention will be readily understood. It will be seen that when the stripping devices are lowered to ground engaging position and the machine is driven forward, the rows of cotton will be guided between the gathering arms and caught between the coacting rolls 47 which are rotated at unequal speed, thereby crushing the cotton stalks and rubbing the cotton bolls from the stalks. The operation of detaching the cotton bolls from 80 the stalks is greatly facilitated and improved by the provision of spiral ribs on the coacting rolls 47 especially when taken in connection with the fact that said rolls are driven at different peripheral speeds. The 85 spiral rib on the roll which is driven at high speed will obviously perform a swiping action with respect to the spiral rib on the roll that is driven at low speed, said action having been found extremely effective in detaching the bolls from the stalks that are passing between the rolls without injury to the cotton staple. The efficiency of the operation is also greatly enhanced by the fact that one of the rolls is spring-pressed in the direction of its mate, permitting the rolls to 90 open apart for the passage of stalks of various dimensions. The stalks when they encounter the shields 62 will be flattened and pass between the side bars of the stripping 95 devices, being left on the ground, while the bolls detached by the rubbing action of the rolls will be taken up by the suction in the ducts 61 and will be carried through the latter and through the wind trunks 60 to the 100 cleaner case. Passing into the cleaner case the material will be subjected to the rubbing action of the cylinder 72 against the riddle C. The fine dust and light material which is thus loosened will be blown out beneath the valve 73 which may be opened to 105 any desired extent. The heavy material and rubbish will pass between the bars of the riddle and will be carried over the bottom plate 74 to the ground while the cotton fiber 110 will be discharged rearwardly over the riddle into the bag 76 to be disposed of as herefore stated.

Having thus described the invention, what is claimed as new is:

1. In a cotton harvester, a pair of coacting rolls each having a spiral rib and means for driving said rolls at unequal peripheral speed for detaching the cotton from the stalk.

2. In a cotton harvester, a pair of coacting rolls each having a spiral rib, means for pressing one of said rolls resiliently in the

direction of its mate, and means for driving said rolls at unequal peripheral speed for detaching the cotton from the stalk.

3. In a cotton harvester, a stripping device comprising spaced bars, a shaft on which said bars are pivotally supported, upright coacting rolls at the front ends of the bars, each of said rolls having a spiral rib, means for resiliently pressing one of the rolls in the direction of its mate, and means for driving the rolls at unequal peripheral speeds.

4. In a cotton harvester, a stripping device comprising spaced bars, a shaft on which said bars are pivotally supported, upright coacting rolls at the front ends of the bars, and gathering arms connected with and extending forwardly with respect to the bars, one of said gathering arms being relatively depressed in a groundward direction.

5. In a cotton harvester, a stripping device comprising spaced bars, a shaft on which said bars are pivotally supported, upright coacting rolls at the front ends of the bars, and gathering arms connected with and extending forwardly with respect to the bars, one of said gathering arms being relatively depressed in a groundward direction and provided with a ground engaging 30 wheel.

6. In a cotton harvester, the combination with a carrying frame of two sets of stripping apparatus, each comprising a pair of bars, gathering arms and coacting stripping rolls at the forward ends of said bars, a shaft on which said bars are pivotally supported at their rearward ends, brackets in which said shaft is supported, one of said brackets being provided with a slot to permit adjustment of the shaft, and means for effecting adjustment of the shaft and retention thereof in adjusted position to cause the two sets of stripping apparatus to be variously spaced apart at their forward 45 ends.

7. In a cotton harvester, a stripping apparatus comprising a pair of bars, coöperating gathering arms and driven stripping rolls at the forward ends of said bars, means for pivotally supporting said bars at their rearward ends, a cross bar connected with one of the bars and extending beneath the other bar, a brace, a bolt connecting said brace with the last mentioned bar, and a 55 spring coiled on the bolt and pressing said last mentioned bar in the direction of its mate.

8. In a cotton harvester, the combination with a carrying frame of two sets of stripping apparatus each comprising two bars one of which is spring pressed in the direction of its mate, gathering arms at the forward ends of said bars, upright coacting gathering rolls at the forward ends of the

bars, and means for driving said rolls at unequal speed.

9. In a cotton harvester, the combination with a carrying frame of two sets of stripping apparatus each comprising two bars one of which is spring pressed in the direction of its mate, gathering arms at the forward ends of said bars, upright coacting gathering rolls at the forward ends of the bars, means for driving said rolls at unequal speed, and means for supporting the bars of each stripping device at their rearward ends for swinging movement in a substantially vertical plane and for rocking movement in a substantially horizontal plane whereby the forward ends of the two stripping devices 75 may be variously spaced apart.

10. In a cotton harvester, a stripping device comprising a pair of spaced pivotally supported bars, gathering arms at the front ends of said bars and upright coacting and driven stripping rolls also supported at the front ends of the bars, in combination with a duct supported on the bars to the rearward of the rollers, and means for inducing the passage of a current of air in a rearward 80 direction through said duct.

11. In a cotton harvester, a stripping device comprising a pair of spaced pivotally supported bars, gathering arms at the front ends of said bars and upright coacting and driven stripping rolls also supported at the front ends of the bars, in combination with a duct supported on the bars to the rearward of the rollers, means for inducing the passage of a current of air in a rearward 90 direction through said duct, and a shield extending laterally and upwardly at the intake mouth of said duct.

12. In a cotton harvester, a wheel supported frame, a stripping apparatus comprising a pair of bars pivotally connected with said frame, of gathering arms at the forward ends of said bars one of said arms being depressed in a groundward direction, upright coacting driven stripping rolls also supported at the front ends of the bars, and means for supporting the stripping apparatus with the gathering arms in a raised position with respect to the ground.

13. In a cotton harvester, a wheel supported carrying frame, a stripping apparatus comprising a pair of bars swingingly connected with the carrying frame for movement in a vertical plane, gathering arms at the forward ends of the bars, and coacting driven upright stripping rolls at the forward ends of said bars; in combination with a receptacle supported on the carrying frame, a cleaner casing containing a driven fan and having an outlet, a wind 115 trunk connecting the outlet of the fan casing with the cleaner casing for the forcible discharge of an air current in the direction 120 125

of said cleaner casing, and a duct connected at its rearward end with the wind trunk, extending forwardly and having an intake mouth to the rearward of the stripping rolls.

14. In a cotton harvester, a cleaner casing containing a driven fan and having an outlet, a wind trunk connecting the outlet of the fan casing with the cleaner casing for the forcible discharge of an air current in the

direction of said cleaner casing, and a duct connected at its rearward end with the wind trunk, extending forwardly and having an intake mouth to the rearward of a pair of cotton stripping rolls, and an upwardly and laterally extending shield at the intake mouth. 15

In testimony whereof I affix my signature.

GEORGE BLOHM.
